UNITED STATES PATENT OFFICE.

MILAN C. BULLOCK, OF CHICAGO, ILLINOIS.

COMPOUND STEAM-ENGINE.

SPECIFICATION forming part of Letters Patent No. 274,437, dated March 20, 1883.

Application filed June 24, 1881. (No model.)

To all whom it may concern:

Be it known that I, MILAN C. BULLOCK, a citizen of the United States, residing at Chicago, in the county of Cook and State of Illinois, have invented certain new and useful Improvements in Compound Steam-Engines; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

15 My invention consists of a two-cylinder steam-engine for operating drilling and hoisting machinery, the steam induction and exhaust devices of which are so constructed and applied that the cylinders and their adjuncts may be 20 used either conjointly, as a compound steam-engine, or separately, as two independent high-pressure steam - engines having a common crank-shaft.

25 In order that my invention may be fully understood, I have illustrated in the annexed drawings, and will describe, the best form thereof at present known to me.

Figure 1 is a front elevation of my improved steam rock-drill. Fig. 2 is a side elevation of 30 the same. Fig. 3 is a vertical longitudinal section in the plane indicated by broken line 1 1 in Fig. 1. Fig. 4 is a transverse section substantially in the two planes indicated by the broken lines 2 2 and x x in Fig. 2, and looking 35 in the direction of the arrow thereon. Fig. 5 is a transverse section substantially in the planes indicated by the broken line 3 3 of Fig. 3, and looking in the direction of the arrow thereon. Fig. 6 is a section in the plane indicated by broken line 4 4 of Fig. 4. Fig. 7 is an isometrical perspective of one of the 40 cross-heads. Fig. 8 is an isometrical perspective of one of the valve-rod guides. Figs. 9, 10, 11, 12, and 13 are detail illustrations of the 45 duplex eccentric. Figs. 14, 15, 16, 17, and 18 are detail illustrations of the steam induction and exhaust devices. Figs. 7 to 18 are drawn on a larger scale than the other figures; but the same letters of reference are used in all the 50 figures to indicate like parts.

All the machinery is supported on the bed-plate A, and the three braced standards A' A²

A³ bolted thereto. The steam-cylinders B and C, bolted to the bed-plate, are set at reverse angles of forty-five degrees to the base thereof, 55 and at right angles to each other. Their piston-rods work through suitable stuffing-boxes in the upper heads of the cylinders, and are connected to the respective pitmen B' and C' by means of cross-heads, preferably such as illustrated in detail in Fig. 7, and running on single guide-bars suitably secured at one end to the cylinder and at the other end to a brace between the standards A' and A².

The cylinders are set in different transverse planes, in order that their pitmen may just pass each other and be connected side by side to the same double crank, D', of the main or crank shaft D. The slide-valve of each cylinder is secured to a stem which terminates at its 70 outer end in a square or polygonal bar, forming a slide which is fitted and moves in a fixed guide secured to the standard A², as shown in Fig. 5, and in detail in Figs. 6 and 8. The two slide-valves are operated by one variable and 75 reversible duplex eccentric, E, provided with the two straps E' and E², from which the respective eccentric-rods E³ E⁴ extend divergently to the slide-valve stems, to which they are pivoted. The eccentric is pivoted at e to an arm, e', fixed 80 on the crank-shaft, which latter passes through a curved slot, e², formed in the eccentric, so that the eccentric may be swung on its pivot e to adjust it with reference to the double crank D'. The curved slot e² of the eccentric is so 85 located and proportioned that the engine or engines may be reversed by swinging the eccentric from one extreme position to the other. The eccentric thus pivoted is connected by a link, e³, to an arm on the adjacent end of a 90 sleeve, F, which is fitted on the crank-shaft, so that it may be turned, but cannot move endwise thereon. The sleeve is constructed with spiral ribs or threads f on its surface, and is encircled by a bush, G', in which spiral grooves 95 g are cut to engage the spiral threads on the sleeve. The bush is fixed in the split end of a tubular slide, G, so as to form a part thereof. The tubular slide is encircled by a ring, G², 100 studs on which are engaged by the forks of the reversing-lever H, by operating which the eccentric may be adjusted at pleasure. The split end of the tubular slide is constructed with ears, so that the segments may be drawn

together by bolts, as shown in Figs. 6, 11, and 12, and lost motion between the spiral threads and spiral grooves be readily taken up.

Of the cylinders, B is the larger and C the smaller. The steam is supplied through the pipe I, governed by the throttle-valve or cock I¹, which is operated by the lever I², through a suitable connecting-rod, I³, pivoted to a crank-pin, i, on the valve-stem. The outlet I⁴ of the throttle-valve has a branch, from which the steam-induction pipe I⁵ leads to and covers the steam-inlet of the steam-chest of the smaller cylinder, C. The outlet I⁴ of the throttle-valve is connected to or forms one branch of the case K of a multi-way valve or cock, the plug K' of which is provided with three separate and distinct passages, k k' k², while the case is constructed with three lateral branches besides the branch I⁴, already mentioned. The exhaust-pipe C^x from cylinder C is connected to the branch K² of the cock. From the branch K³ of the same a jacked steam-induction pipe, K⁴, leads to and covers the steam-inlet of the steam-chest of the larger cylinder, B, while another pipe, K⁶, leads from its branch K⁵ to the coupling L' of the main exhaust-pipe L, with a nipple on the coupling, of which the exhaust-pipe B^x from the larger cylinder, B, is also connected. The plug of the multi-way cock is provided with a lever-handle, K⁷, by which it may be turned.

Whether the steam-cylinders and their adjuncts will operate conjointly as a compound steam-engine or independently as two separate high-pressure steam-engines depends upon the position of the plug of the multi-way cock. If they are to operate as a compound steam-engine, then the plug must be turned to the position shown in Fig. 15, so that live steam is admitted only to the smaller cylinder, 40 and the exhaust-steam therefrom is further utilized by the larger cylinder before it reaches the main exhaust-pipe L. If, on the other hand, they are to operate independently as two separate high-pressure steam-engines, then 45 the plug must be turned to the position shown in Fig. 16, so that live steam will be admitted to both cylinders and the exhaust-steam from each discharged directly into the main exhaust-pipe L.

50 In performing average drilling work, and for hoisting purposes, the engines should be used as one compound steam-engine, in order to economize steam and use it to the best ad-

vantage. When extra power is required the engines should be used independently as two 55 high-pressure steam-engines.

The drilling mechanism may be constructed and mounted and driven in manner shown in the drawings. Detailed description thereof is deemed unnecessary herein, because it forms 60 no part of my present invention. The swivel-head M, carrying the drilling mechanism, is shown as constructed like the swivel-head described and claimed in my application for Letters Patent filed January 27, 1881. 65

Beyond the fly-wheel N a shiftable spur-pinion, O, is mounted on the crank-shaft for driving the hoisting machinery, the hoisting-drum P of which is mounted on a shaft, P', located below the crank-shaft. Detailed description 70 of this hoisting machinery is here omitted, because it is fully described in another application for Letters Patent, (filed of even date with the application for this patent,) wherein all its novel features of construction and arrangement are claimed. 75

The cylinders and their valve-chests are jacketed, and a steam-pipe, R, supplies these jackets and the jacket of steam-induction pipe K⁴ with live steam. 80

The claim covering the valve-shifting mechanism illustrated in the accompanying drawings has been withdrawn from this case in compliance with the requirement of the Patent Office for division. Said valve-shifting 85 gear or mechanism will form the subject of a separate patent.

Having thus described my invention, what I claim is—

The combination, substantially as before set 90 forth, of two steam-cylinders operating on a common crank-shaft, and a multi-way valve or cock adapted to establish steam communication to the steam-induction pipe of one of the cylinders, either from the throttle-valve direct 95 or from the exhaust-pipe of the other cylinder, which is always supplied with steam direct from the throttle-valve.

In testimony whereof I affix my signature in presence of two witnesses.

MILAN C. BULLOCK.
